UNITED STATES PATENT OFFICE

2,470,544

EXERCISING DEVICE

Joseph D. Bell, San Francisco, Calif.

Application September 24, 1948, Serial No. 50,983

7 Claims. (Cl. 272—79)

1

The present invention relates to improvements in exercising devices and has particular reference to a device of the character described in which a seat occupant raises the seat and the weight of his body by pushing forward on a set of foot pedals while the weight of his body returns the seat and the foot pedals to an initial position.

The present invention is a further development of my Pressure Drive Mechanism described in my Patent No. 2,252,156 of August 12, 1941, and also of the Exercising Machine described in my pending application, Serial No. 40,945, filed July 22, 1948, now Patent No. 2,455,548.

In the patented structure it was proposed to use a sliding wedge for raising the seat on a forward pressure on the foot pedals, and in the pending application it was contemplated to use a fixed inclined track and a seat-supporting brace for accomplishing a similar purpose, the brace being operated by the foot pedals.

In the present invention it is proposed to utilize a swingable link for guiding the seat-supporting brace in such a manner that the seat is wedged upward in response to a forward movement of the foot pedals.

It is further proposed to provide a cushioning means for taking the shock at the end of the rearward movement of the brace and for aiding in the initiation of the next forward movement.

Further objects and advantages of my invention will appear as the specification proceeds, and the novel features of my invention will be fully defined in the claims attached hereto.

The preferred form of my invention is illustrated in the accompanying drawing, the sole figure of which illustrates my exercising device in perspective view.

While I have shown only the preferred form of my invention, I wish to have it understood that various changes and modifications may be made within the scope of the claims attached hereto without departing from the spirit of the invention.

In its preferred form my device rests on a main frame 1, having cross-members 2 at the front and rear ends thereof and bent as at 3 to present a raised front section 4 and a rear section 5 disposed substantially in the plane of the two transverse members 2.

A pair of posts 6 rise from the front transverse member 2 in spaced and parallel relation, and are provided, at their upper ends, with a transverse gripping handle 7. Two bars 8 extend forward from the posts intermediate the height thereof and terminate in a bearing 9, in which

2

is supported a yoke 10 carrying a pair of foot pedals 11. A cross-rod 12 connects the legs of the yoke substantially midway of their lengths.

An auxiliary frame 13 is pivoted to the main frame, rearwardly of the posts 6 by means of a bracket 14, the auxiliary frame comprising two frame members 14 extending first upwardly and then rearwardly over the rear portion of the main frame. The rear end of the auxiliary frame carries a seat 15.

Mounted on the rear portion of the main frame is a second post 16 having a pair of links 17 pivotally secured thereto as at 18. The seat-supporting portion of the auxiliary frame has a pair of links 19 suspended therefrom, and the free ends of the links 17 and the links 19 are interconnected as at 20.

A connecting rod 21 has its front end pivoted to the cross-rod 12 of the yoke 10, and has its rear end, in the form shown, connected to the pivot 20 which joins the two links 17 and 19. However, the connecting rod 21 may be pivoted to the links 19 at other points, as at 22, depending upon results desired.

A spring 23 is suitably mounted upon the post 16 to limit the rearward swing of the links 17 and to serve as a shock absorber adapted to give an impetus initiating movement in the opposite direction.

In explaining the operation it might be stated that the different movable parts are shown as being in the position occupied substantially midway of the return stroke. Continuation of the return stroke will cause the pivot 20 to move toward the post 16 on an arc defined by the links 17, with the result that the links 19 swing downward, lowering the seat 15, this movement being brought about by the weight of the seat occupant.

When the seat reaches the lowermost position the links 19 strike the spring 23 and are stopped thereby and are also urged to move in the reverse direction.

As the seat occupant presses on the foot pedals 11 for the forward stroke the rod 21 drags the pivot 20 forward, this pivot being forced to move along an arc defined by the links 17 and to raise the links 19, with the result that the seat 15 is lifted during the forward stroke.

It will thus be seen that on the forward stroke the seat occupant lifts himself by pushing forward on the pedals 11, while on the rearward stroke the weight of the seat occupant causes the different parts to return to an initial position for lowering the seat.

While in the specification I have referred to two posts 6, two links 17 and two links 19, it is apparent that individual posts and links would serve the same functions, and in defining the invention in the claims the pairs will be referred to as individual members.

It should be understood that in their general effect the links 17 serve to wedge the links 19 and the seat 15 upward on the forward stroke of the link 21 and that this action may be broadly compared to the wedging action referred to in my patent hereinabove mentioned.

I claim:

1. An exercising device comprising an elongated main frame having a hand-grip post at its front and a second post rearwardly thereof, a pedal yoke swingable with respect to the frame near the front post, a seat having means for mounting the same above the second post with freedom of up and down movement, a lift link mounted for supporting the seat, a second link having one end swingably connected to the upper part of the second post, and a rod member having one end connected to the yoke, the free ends of the rod member and of the two links being interconnected to cause the second link to serve as a guide for raising the lift link and the seat on a forward movement of the yoke.

2. An exercising device comprising an elongated main frame having a hand-grip post at its front and a second post rearwardly thereof, a pedal yoke swingably supported by the frame forwardly of the front post, an auxiliary frame having a front end pivoted to the main frame rearwardly of the front post and with freedom of up and down movement and having a seat on the rear end thereof, a lift link mounted for supporting the seat, a second link having one end swingably connected to the upper part of the second post, and a rod member having one end connected to the yoke, the free ends of the rod member and of the two links being interconnected to cause the second link to serve as a guide for raising the lift link and the seat on a forward movement of the yoke.

3. An exercising device comprising an elongated frame having a hand-grip post at its front end and a second post rearwardly thereof, a pedal yoke swingably supported by the frame near the front post, a rod pivoted to the pedal yoke, a link pivoted to the second post, the rod

and the link being connected to form a joint adapted for raising and lowering by operation of the pedal yoke, a movable seat, and a seat operating member connected to the link.

4. An exercising device comprising an elongated frame having a hand-grip post at its front end and a second post rearwardly thereof, a pedal yoke swingably supported by the frame near the front post, a rod pivoted to the pedal yoke, a link pivoted to the second post, the rod and the link being connected to form a joint adapted for raising and lowering by operation of the pedal yoke, a seat mounted over the rear post with freedom of swinging movement, and a seat operating member connected to the link.

5. An exercising device comprising an elongated frame having a hand-grip post at its front end and a second post rearwardly thereof, a pedal yoke swingably supported by the frame near the front post, a seat having means for mounting the same above the second post with freedom of up and down movement, a pair of links interconnected to form a joint, one of the links being pivoted to the post and the other being mounted in seat supporting relation, and a rod connecting the pedal yoke and one of the links whereby the seat is raised and lowered in response to operation of the pedal yoke.

6. An exercising device comprising an elongated frame having a hand-grip post at its front end and a second post rearwardly thereof, a pedal yoke swingably supported by the frame near the front post, a seat having means for mounting the same above the second post with freedom of up and down movement, a link mounted in seat supporting relation, a rod pivoted to the pedal yoke and to the free end of the link, and a second link pivoted to the rear post and to the first link near the free end thereof.

7. An exercising device comprising an elongated base frame having a post at its front and a second post rearward thereof, a seat member having a link connected to the same, a second link having one end connected to the first link and the other end to the second post, a foot rest member mounted on the first post and connections between the foot rest member and one of the links operable for raising the seat by the movement of the foot rest member.
